LUTHER L. KNOX, OF AVALON, PENNSYLVANIA, ASSIGNOR TO KNOX PRESSED & WELDED STEEL COMPANY, OF PITTSBURGH, PENNSYLVANIA, A CORPORATION OF PENNSYLVANIA.

FLUE AND VALVE ARRANGEMENT FOR REVERSING REGENERATOR-FURNACES.

1,203,748.

Specification of Letters Patent.

Patented Nov. 7, 1916.

Application filed July 6, 1914, Serial No. 849,280. Renewed February 18, 1915. Serial No. 8,075.

To all whom it may concern:

Be it known that I, LUTHER L. KNOX, a citizen of the United States, residing at Avalon, in the county of Allegheny and State of Pennsylvania, have invented a new and useful Improvement in Flue and Valve Arrangements for Reversing Regenerator-Furnaces, of which the following is a full, clear, and exact description, reference being had to the accompanying drawings, forming part of this specification, in which:

Figure 1 is a view partially in plan and partially in horizontal section of a flue and valve arrangement embodying my invention. Figs. 2, 3 and 4 are sections taken respectively on the lines II-II, III-III and IV-IV of Fig. 1.

My invention has relation to flue and valve arrangements for reversing regenerator furnaces; and is designed to provide an arrangement of this character in which the flues leading from the regenerator to the stack contain air and gas flues of such character and construction as to be of substantially the same level, thereby greatly simplifying the arrangement.

A further object of my invention is to so arrange the air and gas flues, relatively to the regenerators, as to greatly reduce the loss of gas when the furnace is reversed.

The nature of my invention will be best understood by reference to the accompanying drawings in which I have shown a preferred embodiment thereof, and which will now be described, it being premised, however, that various changes can be made in the details of construction and arrangement of the various parts without departing from the spirit and scope of my invention as defined in the appended claims.

In these drawings the numerals 2 and 3 designate the usual gas regenerators and 4 and 5 the air regenerators. 6 designates a stack flue having an outlet connection 7 leading to the stack 8; this stack connection being arranged intermediate of the regenerators.

Connecting one end portion of the stack flue 6 with the respective regenerators 2 and 4 are flues 9 and 10. Similar flues 11 and 12 connect the regenerators 5 and 3 with the other end portion of the stack flue 6. The flues 6, 7, 9, 10, 11 and 12 all have substantially the same floor level and are also

level with the bottom of the regenerator chambers. Arranged above each of the gas flues 9 and 12 is a suitable gas intake valve 13; and opening into the top of each of the air flues 10 and 11 is an air intake valve 14. The valve arrangement for one set of flues is a duplicate of that of the other set of flues and Figs. 3 and 4 may be considered as sections through either set.

Arranged between each gas intake valve 13 and the stack flue is a gas valve or damper 15. An air valve or damper 16 is arranged between each air intake valve 14 and the stack flue 6. The gas and air intake valves are set closely to the entrances 17 to the regenerator chambers; and the air and gas valves or dampers 15 and 16 are set closely in their respective flues to the gas and air intake valves.

The gas and air intake valves and the gas and air valves or dampers may be of any suitable character.

I have illustrated herein a form of intake valve which is specifically described and claimed in my pending application Serial No. 849,164, filed July 6, 1914. This consists of a valve casing having the connection 18 leading to a producer or other source of gas supply and communicating at its lower end with the port 19 leading into the gas flue. This port is controlled by a vertically movable water cooled valve 20 having suitable actuating connections 21 and adapted to seat over the upper end of the port 19 in a water pan 22 which forms a seal for the valve.

The air and gas valves or dampers 15 and 16 are shown as a type specifically described and claimed in my application Serial No. 849,166, filed July 6, 1914, and Patent No. 1,102,197, dated June 30, 1914. Each of these valves is shown as consisting of a hollow water cooled frame 23, extending downwardly and surrounding a flue opening 24 in line with the respective flue which it controls, with a hollow water cooled valve or damper plate 25 arranged to slide within said frame and control the flue opening. These valves are preferably set in inclined position, as shown in Fig. 3.

The operation will be readily understood. When the gas and air intakes at the right hand side (Fig. 1) are closed, the valves or dampers 15 and 16 at that side are opened.

At the opposite side the valves or dampers 15 and 16 are closed and the air and gas intake valves are opened. On reversing the furnace, the gas and air intake valves at 5 the right hand side are opened, the gas and air valves or dampers at that side are closed, the gas and air intake valves at the left hand side are closed and the gas and air controlling valves at that side are opened. 10 The advantages of my invention will be apparent to those skilled in this art since it provides an exceedingly central and efficient flue and valve arrangement for controlling the operation of reversing regenerator furnaces. All the flues being at the 15 same level, the flue structure is easily built and kept in repair. The air and gases are not compelled to make any up and down passes either in going to or returning from 20 the regenerators. The gas intake valves, together with the gas controlling valves or dampers, being set up closely to the entrance

to the regenerator chambers, the waste of gas is reduced to a minimum at each reversal of the furnace.

25

I claim:

In a flue and valve arrangement for regenerative furnaces, the combination of air and gas regenerators, a stack flue running transversely of the regenerators, a continuous port connecting each of the regenerators with said stack flue, said ports being at the same level as the stack flue and all opening directly into the same side of said flue, each port having an admission valve in its upper 30 wall, and each port also having a vertically movable damper between said valve and the stack flue; substantially as described.

In testimony whereof, I have hereunto set my hand.

LUTHER L. KNOX.
